UNITED STATES PATENT OFFICE.

GEORGE KOMARCEVITS, OF CLEVELAND, OHIO.

STREET-CLEANER.

1,353,047.

Specification of Letters Patent. Patented Sept. 14, 1920.

Application filed September 19, 1919. Serial No. 324,795.

To all whom it may concern:

Be it known that I, GEORGE KOMARCEVITS, a citizen of Hungary, residing at Cleveland, in the county of Cuyahoga and State of Ohio, have invented certain new and useful Improvements in Street-Cleaners, of which the following is a specification.

The primary object of the present invention resides in the provision of a street cleaner especially designed for removing snow and ice from pavements and roadways and is in the form of a hand truck employing a fuel tank having a pump device associated therewith and burners positioned adjacent the ground for purposes of directing a flame jet directly on the gathered ice or snow.

With the above and other objects in view, the invention consists in the novel form, combination and arrangement of parts herein fully described and shown in the accompanying drawings wherein like reference characters indicate similar parts throughout the several views.

In the drawing,

Figure 1 is a vertical sectional view of a street cleaner constructed in accordance with the present invention, a fuel tank being shown in section, and

Fig. 2 is a top plan view of the burner set detached from the remaining mechanism.

Referring more in detail to the accompanying drawing, there is illustrated a hand truck embodying supporting wheels 3 journaled upon an axle 4 which in turn supports a platform 5 for carrying all of the parts of the device, a handle 6 being carried by the platform 5 and provided with a grip 7 for purposes of moving the truck over a pavement.

A tank 8 having a filling spout 9 at its upper end closed by a screw cap 10 is adapted to contain a quantity of fuel such as gasoline or kerosene as indicated by the dotted line contents. The rear end of the platform 5 adjacent the handle 6 carries a hand operated pump 11 having a pipe connection 12 with the interior of said tank as at 14 and is supported in a bearing 13 exteriorly of the tank 8. An end valve 15 is provided in the upper end of the pipe 12 for purposes of retaining the air in the tank that is forced therein by the pump 11. A pressure gage 16 is carried by the upper wall

of the tank 8 to indicate the gas volume in the tank.

A burner set is carried by the forward side of the tank 8 and includes a pair of brackets 17 in which is secured a pipe 18 having an extension 19 within the tank, the lower end of the pipe 19 opening adjacent the lower end of the tank and below the level of the fuel therein, a hand valve 20 being provided in the pipe 18 for purposes of controlling the flow of fuel issuing through the pipe 19. A forward rest or foot 21 carries an upstanding support 22 for the extension 23 of the pipe 18 whereby the truck is supported in an upright position as indicated with the foot 21 resting upon the pavement A. The forward projection 23 of the pipe 18 is mounted in the upper end of the support 22 and projects forwardly thereof as indicated in Fig. 1 and is provided with a lateral branch pipe 24 angularly extending therefrom at opposite sides, and to which branch is connected a plurality of S-shaped connectors 25 having the free ends thereof directed into the rear ends of the conically-shaped burners 26 which are provided with a plurality of air openings 27 for purposes of aiding combustion. As shown in Fig. 2, the branch pipe 24 is connected as at 28 to the forward extension 23 of the fuel supply pipe 18 and is rotatable in the connection 28 whereby the angularity of the burners 26 supported on the S-shaped members 25 may be regulated, this change in position being obtained by the provision of a bracket 29 upon the pipe 23 and having pivoted in the upper end thereof, a bell crank 30, one end of which has a link connection 31 with one of the burner members 25 while the other end of the bell crank has a long arm 32 connected thereto, with the handle portion 33 thereof extending in proximity of the handle 7 and provided with a rack 34 engageable with an adjacent part of the handle.

From the above detailed description of the invention, it is thought that the construction and operation thereof will at once be apparent, it being noted that the fuel contents of the container 8 are forced therefrom by the air within the upper end of the container into the outlet pipe 19 of the supply pipe 18, the air being supplied to the tank through the medium of the pump 11, the quantity of which may be determined

by the gage 16 while the petcock 15 prevents the back escape of air from the tank. The angularity of the burners 21 is readily controlled by shifting the arm 32 so as to insure the cleaning of snow and ice at a point directly forward of the truck, while the device is readily transportable during operation by slightly elevating the foot 21 from the ground line A to permit a rolling movement of the supporting wheels 3.

While there is herein shown and described what is believed to be the preferred embodiment of the invention, it is nevertheless to be understood that minor changes may be made in the form, combination and arrangement of parts without departing from the spirit and scope of the invention as claimed.

What is claimed as new is:—

1. A burner for street cleaners including a supply pipe, a branch pipe extending transversely of the outer end thereof and rotatably supported by said supply pipe,

distributing pipes reversely curved at their opposite ends and having one end connected to the branch pipe with the intermediate portion overlying the branch pipe, and jet nozzles supported on the distributing pipes forwardly of the free ends thereof.

2. A burner for street cleaners including a supply pipe, a branch pipe extending transversely of the outer end thereof and rotatably supported by said supply pipe, distributing pipes reversely curved at their opposite ends and having one end connected to the branch pipe with the intermediate portion overlying the branch pipe, jet nozzles supported on the distributing pipes forwardly of the free ends thereof, and means engaging one of said distributing pipes for partially rotating the transverse pipe to vary the inclination of the jet nozzles.

In testimony whereof I affix my signature.

GEORGE KOMARCEVITS.
